FEED CONTROL DEVICE FOR COTTON
CLEANING AND EXTRACTING MACHINES

Orville Mitchell, Dallas, Tex.

Application November 13, 1939, Serial No. 304,031

10 Claims. (Cl. 19—67)

The general object of this invention is to provide a novel feed control device for cotton cleaning and hull extracting machines which will enable a larger variety of speeds to be imparted to the feed rollers than would be feasible with the types of mechanics now employed for that purpose. In other words, in order to secure the number of changes in speed made possible by the present invention, by using the types of mechanism now employed, which usually comprise a belt drive involving pulleys of different sizes, such a large number of such pulleys would have to be employed as to be utterly impracticable.

In cotton cleaning and hull extracting machines there are two feeder rollers which serve the purpose of withdrawing the cotton from a hopper above and feeding it at a desired rate of speed, varying from $\frac{1}{2}$ R. P. M. minimum to 3 R. P. M. maximum, to the extracting and cleaning mechanism below.

The rate of feed must be varied to suit the capacity of the gin-stand on which the extractor-cleaner is mounted, some types of gin-stands having more capacity than others. Also, the rate of feed must be varied to suit the type and condition of the cotton. Certain breeds of cotton should be ginned more slowly than others, and the feed of the extractor-cleaner has to be reduced accordingly. Green or damp cotton must be fed much more slowly than dry cotton. Long-staple cotton must be fed more slowly than short-staple. Cotton containing a large percentage of hulls and other trash has to be fed into the extractor-cleaner at a much higher rate of speed than clean, hand-picked cotton, for the reason that so large a percentage of the incoming material is waste, destined for the hull pile, and does not go into the gin-stand at all.

These variations in type, condition, or trash content often vary from one wagonload to the next, requiring frequent changes in the rate at which the feeder rollers rotate. Therefore, a mechanism to control the rate at which the cotton is fed—that is, the rate at which the feeder rollers rotate—in order to be efficient must be capable of quick and accurate change through a range of speed variations extending from $\frac{1}{2}$ R. P. M. minimum through several intermediate steps to 3 R. P. M. maximum.

A second important requirement of the feed control device is the ability to shut off the feed altogether, at the will of the operator. Between bales, the feed is always stopped; the purpose of this is to get all of the cotton from one wagonload out of the machinery before the cotton from

the next wagonload enters the machinery. Also, it is frequently necessary to stop the feed on one extractor-cleaner in order to throw that particular machine or the gin under it temporarily out of operation, for the purpose of making repairs or removing extraneous matter that has been sucked up with the cotton, or for unchoking a congestion of some kind.

My improved control device accomplishes both of the desired results in a highly satisfactory manner and is greatly superior to either of the two systems generally used in the past. These two systems are the ratchet and pawl arrangement shown by Patent No. 1,360,132, and the cone-pulley-gearred arrangement, shown by Patent No. 1,682,140.

My present invention finds its preferred embodiment in an expansible pulley for driving a receiving pulley by means of a V-belt, this receiving pulley being operatively connected to the feeder rollers, and being mounted on an arm which is pivoted to permit changing the centers between the two pulleys. As the pulley centers are changed, the expansible pulley opens or closes, causing the V-belt to run deeper or shallower in the groove, thereby changing the effective diameter and, as a consequence, changing the rate of speed at which the driven pulley causes the feeder roller to operate.

It will be readily seen that an infinite number of gradations in speed between the minimum and maximum can be obtained. However, in actual practice we find that eight or nine speeds answer all practical requirements, and no good purpose would be subserved in providing more gradations than that number.

To throw the feed on or off, I employ a clutch which operates on the mechanism that transmits the power from the receiving pulley to the feeder rollers. When the clutch throws the transmitting mechanism out, the feeder rollers stop; when the clutch throws the transmitting mechanism into operation, the feeder rollers resume their rotation at whatever speed the expansible pulley is set to rotate.

It may be stated at this point that the clutch mechanism does not necessarily need to be operated between the receiving pulley and the feeder rollers. It can be located as well between the high speed driving shaft and the expansible pulley. In other words, the stopping-and-starting device, whether it be a clutch, a belt tightener, or other device for this purpose, can be located either before or after the variable speed device, the latter consisting of the expansible

pulley, the receiving pulley, and the V-belt for driving from one to the other.

My invention, therefore, may be conceived in two broad aspects, one involving a constantly rotating expansible pulley with V-belt and receiving pulley and a clutch or other stopping-and-starting device operating on the transmission between the receiving pulley and the feeder rollers; and the other involving transmitting mechanism between a high-speed shaft and the expansible pulley on another shaft, with the stopping-and-starting device operating on the transmission at this point, whereby to cause the expansible pulley itself and everything that follows it to operate or not to operate, as desired.

Of the two, the former is by far the preferred arrangement, and the one illustrated in the drawings. The second arrangement is not illustrated, as it simply involves a mere different mechanical arrangement of the same parts for accomplishing the same purpose, which not only comes within the scope of my invention, but would be obvious to any skilled mechanic.

In the drawings:

25. Figure 1 is an end elevation looking at the right hand end of the machine;

20. Figure 2 is a similar view looking at the left hand end of the machine;

25. Figure 3 is a view similar to Figure 1 the upper portion of the casing being in section to show the feed rollers;

30. Figure 4 is a section taken on the line 4—4 of Figure 1 and showing a main operating shaft moved to the right to disengage the clutch mechanism;

35. Figure 5 is a view similar to Figure 4, the shaft being moved to the left to engage the clutch mechanism;

40. Figure 6 is a sectional view, enlarged, taken on the line 6—6 of Figure 5;

45. Figure 7 is a sectional view, enlarged, of the receiving pulley driven by the V-belt taken on the line 7—7 of Figure 1;

50. Figure 8 is a cross section, enlarged, taken on line 8—8 of Figure 4;

55. Figure 9 is a cross section, enlarged, taken on the line 9—9 of Figure 4;

60. Figure 10 is a sectional elevation, enlarged, taken on the line 10—10 of Figure 1;

65. Figure 11 is a cross section, enlarged, taken on the line 11—11 of Figure 1;

70. Figure 12 is a sectional view, enlarged, taken on the line 12—12 of Figure 1;

75. Figure 13 is a sectional detail view, enlarged, taken on the line 13—13 of Figure 1; and

Figure 14 is a detailed view of a conventional expansible pulley.

Referring now to the drawings the numeral 1 indicates the casing of the machine mounted on 60 supports 2. Suitably mounted in the side walls of the machine is a high speed shaft 3 adapted to run at about 100 R. P. M., on which is mounted an expansible pulley 4. The type of expansible pulley shown (Figure 14) consists of two sections 65 4 and 5 with sloping walls facing each other to provide between them a seat for the V-belt 6. The section 4 is set-screwed to the shaft, but the section 5 is splined to the shaft so as to be rotated thereby but at the same time being capable of axial movement thereon. The numeral 7 indicates a barrel inside of which is a coil-spring 8 bearing against the section 5 and tending to keep it in contact at all times with the V-belt 6. This spring, by reason of the pressure it exerts 75 against the sliding section 5, prevents the V-belt

from running any deeper in the groove of the pulley than provided for by the setting or adjusting mechanism that will be described later. The V-belt 6 is received by and drives the receiving pulley 9. This receiving pulley is a conventional 5 type of V-belt sheave mounted on a stud 10, which is journaled in one end of an arm 11. This arm 11 is provided with a sleeve 12, Figures 1, 4 and 5, by means of which it is pivoted on one end of a shaft 13, intermediate its ends, and at its outer end is pivotally secured at 14 to the upper end of a connecting rod 15, which in turn is connected at its lower end to a lever 16 (Figure 12). This lever 16 is set-screwed on the outer end of a tube 17, which is journaled in bearings at 18 and 19 15 so as to be capable of rotation through slightly more than a quarter of its circumference. Mounted near the opposite end of the tube 17 and set-screwed to it is a handle 20, by means of which the tube may be turned. As the operator 20 pulls down on this handle, the tube 17 and the lever 16 are rotated in a clockwise direction, the connecting rod 15 is pulled down, the arm 11 pivots and the receiving pulley 9 is raised. This increases the distance between the centers of the 25 receiving pulley 9 and the expansible pulley 4 and causes the V-belt to run deeper in the expansible pulley, which shifts section 5 of said pulley to the right against the resistance of spring 8 in the barrel 7, thereby decreasing the speed of the 30 receiving pulley 9.

On the other hand, when the handle 20 is raised the tube 17 and the lever 16 are rotated in an anti-clockwise direction, the connecting rod 15 is moved up, and the front end of the arm 35 11, carrying the receiving pulley 9 is depressed. This decreases the distance between the centers of the pulleys and causes the V-belt to run shallower in the expansible pulley, the sliding section 5 being pushed in toward the section 4 by reason 40 of the tension of the spring in the barrel 7, thereby increasing the speed of the receiving pulley 9.

The numeral 21, Figure 11, indicates a notched segmental plate 21 which is secured to the end frame 22 of the machine as indicated at 23. 45 Mounted on the handle 20 is a detent 24, co-operating with the notches 25, and operating in the conventional manner to hold the handle 20 and the tube 17 fixed in the position to which they have been adjusted. The notches are eight in 50 number and are designated by numerals stamped on the segmental plate, so as to indicate to the operator the position to which the handle is set, "1" designating the lowest rate of speed, "8" the highest rate of speed, and the other six numerals 55 55 the intermediate rates of speed.

I will now describe the manner in which the power is transmitted from the receiving pulley 9 to the feeder rollers 26, which are inside the machine and mounted on the shafts 27 and 28, 60 which extend in parallel relation transversely of the machine.

Attached to the face of the receiving pulley 9 is a pinion 29 (Figure 7), which meshes with and drives a gear 30. The gear 30 is set-screwed to the shaft 13, near one end of the latter. This shaft extends completely through the machine, extending out far enough on the right to receive not only the gear 30 but also the sleeve 12 of the pivoted arm 11, and extending far enough at the 70 left to take the transmitting mechanism to be described.

Idling on the left hand end of shaft 13 is a sprocket 31 for driving, by means of a chain 32, a sprocket 33 which is set-screwed to a shaft 27 75

of the front feed roller. Just behind this sprocket 33 is a gear 34, also set-screwed to the shaft 27, which meshes with a gear 35 set-screwed to the shaft 28 of the rear feeder roller. By means of these two gears, both having the same number of teeth, the front feeder shaft causes the rear feeder shaft to rotate at the same speed but in the opposite direction, the two feeder rollers revolving slowly toward each other at the top, thereby withdrawing the cotton from the distributor hopper, compressing it into the space between the feeder rollers and feeding it to the extracting and cleaning mechanism below.

What I have described so far pertains to the mechanism for driving the feeder rollers at varying rates of speed to suit the will of the operator. I will now describe the mechanism for stopping the feed altogether.

Located inside of the tube 17 previously referred to is a shaft 36, on the front end of which is set-screwed a handle 37, by means of which the shaft 36 can be rotated for slightly more than a quarter of a revolution. On the rear end of this shaft, where it protrudes beyond the tube 17, is set-screwed an arm 38, which in turn is fastened to a connecting rod 39 (Figures 1 and 12). The upper end of the connecting rod 39 is secured to a lever 40 set-screwed to a shaft 41 journaled in suitable bearings 42 on the end of the machine. On the opposite end of the shaft 41 is a rocker arm 43 (Figures 4 and 5) set-screwed to the shaft and provided in its end with a groove 44 for engaging a pin 45. This pin is fastened in the bearing 46 in which the shaft 13 is journaled. As the rocker arm 43 is rocked, it engages the pin 45 and causes the bearing 46 and the shaft 13 to be moved endwise. The bearing 46 is mounted in a holder 47 which is in the form of a section of steel tubing welded to the end frame 48 of the machine, and which is slotted as indicated at 49 in Figure 6 to permit the pin 45 to project through it. The bearing 46 is a bronze bushing adapted to slide endwise $\frac{3}{16}$ " as said bushing and the shaft 13 are shifted to the right or left. A collar 50 secured on shaft 13 adjacent the end of bearing 46 causes the shaft 13 to move with the bearing. The bearing 46 is positioned between the gear 30 on the outside (Figures 4 and 5) previously referred to and the collar 50 on the inside, with result that whenever the bearing itself is shifted in either direction, the shaft 13 has to move with it. The extent to which the shaft and the bearing shift is, as stated, only $\frac{3}{16}$ ", this being sufficient to cause engagement or disengagement of the clutch mechanism, to be later described. When the shifting occurs, the V-belt 6 inclines away from the vertical at the top, to the extent of $\frac{3}{16}$ ", each way, corresponding to the total movement of the shaft, as referred to above. The clutch mechanism which I employ will now be described, although any other desired form of clutch mechanism could be used, as I have previously indicated.

As has already been stated, and as clearly shown in Figures 4 and 5, the shaft 13 extends completely through the machine and projects far enough beyond the left hand end of the machine to receive the clutch mechanism. 51 indicates the bronze bearing in which the shaft 13 is journaled at the left hand end of the machine. The sprocket 31, previously referred to, has an extended hub 52, integral with which is a sprocket-shaped clutch member 53, shown on an enlarged scale in Figure 9. This assembly is

bushed at 54 so as to permit it to idle on the shaft 13. The opposing clutch member 55 is set-screwed to the shaft 13, as shown at 56, so as to turn with it, and is provided with a plurality of pins 57 (Figure 8) for engaging the sprocket-shaped clutch member 53. When the shaft 13 is shifted to the right, as shown by Figure 5, the pins 57 engage the sprocket-shaped member 53, causing it to rotate, and with it the sprocket 31, which in turn drives the chain 32 and the feeder 10 rollers. On the other hand, when the shaft is shifted to the left, as shown by Figure 4, the pins 57 and the clutch member 53 disengage, and the sprocket 31 stops rotating, as do the chain and the feeder rollers. Mounted in a recess in the 15 clutch member 53 and extending into a corresponding recess in the clutch member 55 is a coil spring 58, which serves the purpose of insuring disengagement of the two clutch members when the shaft 13 is shifted to the left; without this 20 spring, the floating member 53 would follow the member 55, when the shift is made.

From the foregoing description it will be obvious that when the operator pulls down on the handle 37, the shaft 36 and the lever 38 are 25 caused to rotate, pulling down on the connecting rod 39, actuating the rocker arm 43 and causing an endwise shift of the shaft 13 and with it the clutch member 55, so as to cause its engagement with the other member 53, driving the chain 30 32 and causing the feed rollers to rotate. On the other hand, the handle 37 is raised, the operations are in an opposite direction, the clutch mechanism is disengaged, and the rotation of the feeder rollers stops.

Referring to Figures 1 and 13, I have shown a coil-spring 59 connected at its upper end, as indicated at 60 to the connecting rod 15, near the upper end of the latter, and at its lower end as indicated at 61 to the connecting rod 39, near the 40 lower end of the latter. This spring is normally under tension, and operates to assist the downward movement of connecting rod 15 and the upward movement of connecting rod 39.

In Figures 1 and 2 I have shown by dotted lines 45 the driving mechanism for operating the rotating members within the machine. As such mechanism is purely conventional consisting as indicated, of belts running over pulleys, it is not considered necessary to describe the same as, 50 aside from the feeder rollers, the invention is in nowise concerned with the mechanism for extracting and cleaning cotton.

I claim:

1. In a feed control device for cotton cleaning 55 and extracting machines, in combination with a pair of feed rollers, a high speed driving shaft, means for rotating said rollers therefrom at a relatively slow rate of speed, a unitary adjustable change speed device, manual means for adjusting 60 said change speed device to change at will the speed of rotation of said rollers, clutch mechanism associated with the feed roller drive, and manual means for operating said clutch mechanism to stop and start the rotation of the feed 65 rollers at will.

2. In a feed control device for cotton cleaning and extracting machines, in combination, a high speed driving shaft and low speed feeder rollers, a spring-controlled expansible driving pulley 70 rotated by the high speed shaft, a receiving pulley, a V-belt operating over the expansible pulley and said receiving pulley to rotate the latter, manually-operated means for moving the receiving pulley toward or from said expansible 75

5. pulley to vary the effective diameter of the expansive pulley so as to increase or decrease the speed of the receiving pulley, means for transmitting power from the receiving pulley to the feeder rollers to rotate the latter, and a clutch mechanism for throwing the transmitting means into or out of operation at the will of the operator.
10. 3. In a feed control device for cotton cleaning and extracting machines, in combination, a high speed driving shaft and low speed feeder rollers, an expansive driving pulley rotated by the high speed shaft, an arm pivotally mounted on the machine intermediate its ends, a receiving pulley journaled on said arm, a V-belt operating over said expansive pulley and receiving pulley to rotate the latter, transmitting means for transmitting power from the receiving pulley to the feeder rollers to rotate the latter, and manually operated 15 lever mechanism mounted on the machine for pivoting said arm in one direction or the other to increase or decrease the distance between the centers of said receiving pulley and said expansive pulley for varying the effective diameter of 20 the latter so as to increase or decrease the speed of the receiving pulley.
15. 4. In a feed control device for cotton cleaning and extracting machines, in combination, a high speed driving shaft and low speed feeder rollers, an expansive driving pulley rotated by the high speed shaft, an arm pivotally mounted intermediate its ends on the machine, a receiving pulley journaled on one end of said arm, a rod pivotally connected at its upper end to the other end of said 25 arm, a V-belt operating over said expansive pulley and said receiving pulley for rotating the latter, transmitting means for transmitting power from the receiving pulley to the feeder rollers to rotate the latter, a lever pivotally mounted on the machine and pivotally connected to the lower end of said rod, and means for turning said lever through selected arcs of movement whereby to raise or lower said receiving pulley and thereby vary the effective diameter 30 of the expansive pulley to decrease or increase the speed of the receiving pulley accordingly, and transmitting means for transmitting power from the receiving pulley to the feeder rollers to rotate the latter.
30. 5. In a speed control device for cotton cleaning and extracting machines, in combination, a high speed driving shaft and low speed feeder rollers, an expansive driving pulley rotated by the high speed shaft, a receiving pulley, a V-belt operating over said expansive pulley and said receiving pulley to rotate the latter, a shaft, and means for driving the same from said receiving pulley, clutch mechanism mounted on said shaft, one member thereof being fixed to the shaft, driving 35 means associated with the other member of the clutch for rotating the feeder rollers, means for varying the effective diameter of the expansive pulley to increase or decrease the speed of the receiving pulley, and manually operated lever mechanism for moving said shaft longitudinally in one direction or the other to engage or disengage the members of said clutch mechanism to rotate, or stop the rotation of said feeder rollers.
40. 6. In a feed control device for cotton cleaning and extracting machines, in combination, a high speed driving shaft and low speed feeder rollers, an expansive driving pulley rotated by the high speed shaft, an arm pivotally mounted on the machine intermediate its ends, a receiving pulley 45 journaled on one end of said arm, a rod pivotally

connected at its upper end to the other end of said arm, a V-belt operating over said expansive pulley and said receiving pulley to rotate the latter, a tube journaled on one end of the machine, a lever on said tube for turning it through selected 5 arcs of movement whereby by means of said rod and arm to raise or lower the receiving pulley to cause said V-belt to change the effective diameter of said expansive pulley, a transverse shaft and means for rotating the same from said receiving 10 pulley, clutch mechanism mounted on said shaft, one member of which is secured to the shaft and the other loose thereon and constituting one element of driving mechanism for rotating said feeder rollers, said shaft being movable endwise in 15 either direction in its bearings, a stud on said shaft, a cross shaft having a slotted rocker arm thereon for engaging said stud, a lever on said cross shaft, a shaft journaled in said tube and having a lever at one end, a rod pivotally connected at its lower end to the latter lever and at its upper end to the lever on said cross shaft, and a handle for turning the shaft mounted in the tube to rock said cross shaft and thereby to cause 20 said rocker arm to move said transverse shaft in 25 one direction or the other to engage or disengage the members of said clutch mechanism whereby to rotate the feeder rollers or to stop their rotation.

7. In a feed control device for cotton cleaning and extracting machines, in combination with a pair of feed rollers, a high speed driving shaft, means, including a slidable shaft, for rotating said rollers therefrom at a relatively slow rate of speed, a unitary adjustable change speed device, 30 manual means for adjusting said change speed device to change at will the speed of rotation of said rollers, clutch mechanism associated with the feed roller drive, one member whereof is mounted on said slidable shaft, and manual means for 35 moving said slidable shaft in one direction or the other to engage or disengage the members of said clutch mechanism to rotate, or stop the rotation of said feed rollers.

8. In a feed control device for cotton cleaning and extracting machines, in combination, a high speed driving shaft and low speed feeder rollers, an expansive driving pulley rotated by the high speed shaft, a receiving pulley having a pinion thereon, a V-belt operating over the expansive 40 pulley and said receiving pulley to rotate the latter, means for varying the effective diameter of the expansive pulley to increase or decrease the speed of the receiving pulley, a slidable shaft having a gear thereon in mesh with said pinion, clutch 45 mechanism mounted on said slidable shaft, one member whereof is fast, and the other loose thereon, driving mechanism operatively connecting the loose member of said clutch with said feed rollers and manual means for moving said slidable 50 shaft in one direction or the other to engage or disengage the members of said clutch mechanism to rotate, or stop the rotation of said feed rollers.

9. In a feed control device for cotton cleaning and extracting machines, in combination, a high 55 speed driving shaft and low speed feeder rollers, an expansive driving pulley rotated by the high speed shaft, a receiving pulley, a V-belt operating over the expansive pulley and said receiving pulley to rotate the latter, means for varying the effective 60 diameter of the expansive pulley to increase or decrease the speed of the receiving pulley, means for transmitting power from the receiving pulley to the feeder rollers to rotate the latter, clutch mechanisms for throwing the transmitting means 65

into or out of operation at the will of the operator, and a slidable shaft constituting one element of the means for transmitting power from the receiving pulley to the feeder rollers operatively connected with said clutch mechanism and manually movable to open or close the same.

5. 10. In a feed control device for cotton cleaning and extracting machines, in combination, a high-speed driving shaft and low-speed feeder 10 rollers, an auxiliary shaft, an expandible driving pulley rotated by the high-speed shaft, a receiving

pulley adapted to drive the auxiliary shaft, a V-belt operating over the expandible pulley and said receiving pulley to rotate the latter, means for varying the effective diameter of the expandible pulley so as to increase or decrease the speed of the 5 receiving pulley and of the auxiliary shaft, means for transmitting power from the auxiliary shaft to the feeder rollers to rotate the latter, and separate means for throwing the transmitting means into or out of operation at the will of the operator. 10

ORVILLE MITCHELL.
